UNITED STATES PATENT OFFICE

GUSTAF ANATOLIUS TÖRNBLOM, OF STOCKHOLM, SWEDEN.

DEVICE FOR GRINDING THE TIGHTENING SURFACE AROUND DOOR HOLES OF STEAM BOILERS AND THE LIKE.

Application filed December 12, 1924, Serial No. 755,540, and in Sweden June 11, 1923.

This invention relates to an improved device for grinding the tightening surface around door holes of steam boilers and the like.

5 The object of the invention is to provide a device of said kind which is simple in construction and convenient and reliable in use.

The invention consists in the combination and arrangement of parts more particularly described herebelow with reference to the accompanying drawings and pointed out in the claims.

In the drawing illustrating one embodiment of my invention Fig. 1 is a front elevation of the grinding device, partly in section, on line A—B of Fig. 2, and a guide plate supporting the same. Fig. 2 is a view from above of the grinding device and its supporting plate showing in section the wall 20 of a superheater box. Fig. 3 is a sectional view of the grinding device and a portion of a superheater box. Fig. 4 is an enlarged section on the line 4—4 of Fig. 3.

Referring to the drawing, 1 designates a 25 guide plate formed with an opening 2 the shape of which corresponds to the opening around which the tightening surface is to be ground, in the present case the door hole 3 of a superheater box 4. Bearing against 30 each side of the guide plate 1 is a bar 5 and 6. Between these bars a sleeve 7 is provided, the length of which slightly exceeds the thickness of the guide plate 1 around the opening 2. Through the said sleeve 7 and corresponding openings in the bars 5 and 6 is inserted a sleeve 8 bearing by means of a flange 9 against the outer side of the bar 5 and having a screw-threaded portion 8¹ on which is provided a nut 10. 35

40 By means of this nut and the sleeve 8 the bars 5 and 6 can be pressed against the ends of the sleeve 7. The sleeve 7 is formed with a radially extending rod shaped projection 7¹ which is surrounded by a spring 11 bearing at one end against the sleeve 7 and at the other end against the bottom of a recess 12¹ of a semicylindrical member 12 formed with lateral pins 12² which slidably engage slots 5¹ and 6¹ of the bars 5 and 6 respectively. The said spring 11 is adapted to keep the sleeve 7 and the semi-cylindrical member 12 in engagement with opposite sides of the opening 2 of the guide plate 1. The projection 7¹ of the sleeve 7 and the spring 11 pass through a hole of

a bolt 13 (Fig. 4) inserted through corresponding holes of the bars 5 and 6. The intermediate portion of said bolt is of larger diameter than the end portions thereof so as to form shoulders against which the bars 5 and 6 bear. The latter are pressed against said shoulders by means of nuts 14 and 15. Between said nuts and the bars 5 and 6 washers 16 and 17 may be provided. Between the nut 14 and the bar 5 is disposed a plate 18 covering the slot 5¹. The sleeve 8 constitutes the bearing for a rotatable shaft 19 supporting at one end a grinding disc 20 of well known construction. The said grinding disc is kept in 70 position by means of an inner disc 21 bearing against a shoulder 22 of the shaft 19 and an outer disc 23 which is pressed against the grinding disc by means of a nut 24 and a locking nut 25.

Near the outer end the shaft 19 has an enlarged portion 19¹ forming a shoulder 19² against which a ball bearing 26 is pressed by means of a disc 27 and a nut 28 screwed onto the sleeve 8. The said nut 28 has outer 80 screw threads and on the same is screwed a nut 29 and a locking nut 30. It will be easily understood that by turning the nut 29 in one direction the nut 28 will be rotated in such direction as to move the ball bearing 26 and thus the shaft 19 to the right in Fig. 3, whereby the grinding disc 20 may be brought in contact with and pressed against the wall of the box 4. When the shaft 19 has been adjusted the nut 28 may 90 be locked by means of a locking nut 38. Surrounding the enlarged portion 19¹ of the shaft 19 is a socket 31 which is kept in position by means of a nut 32 pressing the said socket against a shoulder 29¹ of the 95 nut 29. Outside the enlarged portion 19¹ of the shaft 19 the latter has a portion 19³ of square shaped cross section adapted to be connected to a flexible shaft the cover of which is adapted to be secured to the socket 100 31. The bar 6 is provided with two handles 33 by means of which the grinding devices may be manipulated as described herebelow.

In the construction form shown in the 105 drawing the guide plate 1 may be kept in position during the grinding operation by means of a cross shaped body 34 which is inserted through a door hole of the superheater box adjacent to that door hole, the 110

tightening surface of which is to be ground. The arms of said body 34 are pressed against the inner side of the wall of the superheater box 4 by means of a screw bolt 35 having outside the guide plate 1 a nut 36. Three set screws 37 bearing against the outer side of the superheater box 4 are used to determine the distance between the guide plate 1 and the box 4 and also to adjust the guide plate into a position exactly parallel with the wall of the superheater box.

When the grinding device has been placed in the position shown in the drawing and the shaft 19 put in rotation the bars 5 and 6 are by means of the handles 32 and 33 moved in such manner that the grinding disc is carried along the edge of the opening 2. As the spring 11 always keeps the sleeve 7 and the member 12 in contact with the edge of the hole 2 even when the bars 5 and 6 take up a diagonal position in relation to the opening 2 the manipulation of the grinding device is very easy and convenient.

25 I claim:—

1. A device for grinding the tightening surface around door holes of steam boilers and the like, comprising a guide plate having an opening of the same shape as the door hole to be ground, bars bearing against opposite sides of the guide plates, a bearing supported by said bars, means including the bearing connecting the bars to each other, a rotary shaft mounted in said bearing, a grinding disc carried by said shaft, and means to maintain the bearing in proximity to the periphery of said opening.

2. A device of the character described, comprising a guide plate having an opening therein, bars on opposite sides of the plate, a bearing supported by said bars, means including the bearing connecting the bars, a sleeve surrounding the bearing within the opening, means connected with the sleeve to maintain the bearing in proximity to the periphery of said opening, and means whereby the bearing is moved around the opening.

3. A device of the character described, comprising a guide plate having an opening therein, bars on opposite sides of the plate, a bearing mounted in said bars, means including the bearing connecting the bars, a sleeve surrounding the bearing within the opening, a slide bearing against the periphery of said opening, and a spring interposed between the slide and sleeve whereby the bearing is yieldingly held in proximity to the periphery of the opening.

4. A device of the character described, comprising a guide plate having an opening therein, supports on opposite sides of the plate, a bearing mounted in the supports, means connecting to supports and bearing, a sleeve surrounding the bearing within the opening, a radial extension on the bearing, a slide interposed between the extension and the periphery of the opening, and a spring surrounding the extension and abutting against the slide and sleeve, whereby the latter is held in contact with the periphery of the opening.

In testimony whereof I have hereunto subscribed my name.

GUSTAF ANATOLIUS TÖRNBLOM.
